Primary Examiner — R. Johnson(74) *Attorney, Agent, or Firm* — Rashauna Norment(57) **CLAIM**

The ornamental design for an adjustable bra, as shown and described.

DESCRIPTION

FIG. 1 is a perspective view of an adjustable bra, showing my new design;

FIG. 2 is another perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right-side elevation view thereof; and,

FIG. 9 is another view of FIG. 1, showing each front panel of the adjustable bra having a removable cup member.

The broken lines showing removable padding in FIG. 9 is for the purpose of illustrating environment and forms no part of the claimed design.

1 Claim, 9 Drawing Sheets(56)
